CHAFING DISH FOR FONDUE OR THE LIKE

Joseph B. Stier, Brooklyn, N.Y., assignor to Styson Inc., New York, N.Y.

Filed May 14, 1970, Ser. No. 22,986

Term of patent 14 years

Int. Cl. D7—02

U.S. Cl. D44—15

FIG. 1 is a front elevational view of a chafing dish for fondue or the like showing my new design;

FIG. 2 is a top plan view;

FIG. 3 is a plan view on line 3—3 of FIG. 1; and
FIG. 4 is a plan view on line 4—4 of FIG. 1.

I claim:

The ornamental design for a chafing dish for fondue or the like, substantially as shown.
